CLAIM

The ornamental design for a retaining box for slide fastener as shown and described.

DESCRIPTION

FIG. 1 is a perspective view of a retaining box for slide fastener according to the first embodiment, showing our new design;

FIG. 2 is a front view of the retaining box of FIG. 1;
FIG. 3 is a rear view of the retaining box of FIG. 1;
FIG. 4 is a left side view of the retaining box of FIG. 1;
FIG. 5 is a right side view of the retaining box of FIG. 1;
FIG. 6 is a top view of the retaining box of FIG. 1;
FIG. 7 is a bottom view of the retaining box of FIG. 1;
FIG. 8 is a perspective view of a retaining box for slide fastener according to the second embodiment, showing our new design;
FIG. 9 is a front view of the retaining box of FIG. 8;
FIG. 10 is a rear view of the retaining box of FIG. 8;
FIG. 11 is a left side view of the retaining box of FIG. 8;
FIG. 12 is a right side view of the retaining box of FIG. 8;
FIG. 13 is a top view of the retaining box of FIG. 8; and,
FIG. 14 is a bottom view of the retaining box of FIG. 8.
The broken lines in the drawings are for the purpose of illustrating portions of the retaining box for slide fastener that form no part of the claimed design.
